UNITED STATES PATENT OFFICE.

CARL A. JOHNSON, OF WORCESTER, MASSACHUSETTS.

MEAT CHOPPER.

Application filed July 19, 1921. Serial No. 485,933.

To all whom it may concern:

Be it known that I, CARL A. JOHNSON, a citizen of the United States, residing at Worcester, in the county of Worcester and State of Massachusetts, have invented a new and useful Meat Chopper, of which the following is a specification.

This invention relates to a meat chopper of the type in which the meat is cut by rotating knife blades which co-act with a perforated die plate, the meat being fed toward the plate by a feed screw of coarse pitch.

My invention relates particularly to certain improvements in details of construction in meat choppers of this type by which the mechanism is made more reliable and satisfactory in operation and the utility of the machine is increased and its life prolonged.

With this general object in view, important features of my invention relate to an improved construction of the perforated die plate, and to improvements in the construction of the rotating knife blades, as will be hereinafter described and more particularly pointed out in the appended claims.

A preferred form of my invention is shown in the drawings in which—

Fig. 1 is a partial sectional elevation of a meat chopper embodying my improvements; Fig. 2 is a separated view of the perforated die plate and its bearing;

Fig. 3 is a front view of the die plate;

Fig. 4 is a front view of the body portion of the rotating cutter;

Fig. 5 is a detail sectional view taken along the line 5—5 in Fig. 4;

Fig. 6 is a front view of the complete cutter, and

Fig. 7 is a sectional view taken along the line 7—7 in Fig. 6.

Referring to the drawings, I have shown portions of a meat chopper including a frame or body 10, a perforated die plate 11, a cap 12 for securing the die plate to the body, and a feed screw 13 having a shaft 14 rotatable in a bearing 15 threaded into an axial opening 16 in the die plate 11.

The threaded opening 16 is preferably slightly countersunk at each face as shown

in Fig. 2 and the bearing 15 is provided with a shoulder 17 adapted to seat firmly against either face of the die plate 11. The perforations 18 in the die plate are of uniform diameter throughout their length and both faces of the plate are provided with accurately finished surfaces. The bearing 15 may be inserted against either side of the plate 11 which is thus reversible and provides for double wear of the plate.

A cutter 20 is mounted on the shaft 14 at the end of the feed screw 13 and is preferably provided with a square hole 21 fitting a squared portion 22 of the shaft.

The cutter is of special construction and comprises a body 23 having integral projecting arms 24, preferably of recessed and substantially L-shaped cross-section as shown in Fig. 5. These parts 23 and 24 are commonly formed integral as a single casting or drop forging.

The cutting blades 25 are of the substantially triangular cross-section shown in Fig. 7 and are preferably secured in the arms 24 by brazing or by any similar process by which the parts are secured to each other by a thin interposed layer of metal 26.

In the preferred construction a shoulder or projection 27 is formed on the under side of the blade 25 and engages an edge 28 of the arm 24, thereby accurately locating the plate.

With this construction it is possible to use a very high grade of steel in the cutting edges and the operation of the machine is correspondingly improved.

Having thus described the features of my invention, it will be evident that changes and modifications can be made therein by those skilled in the art within the spirit and scope of my invention as set forth in the claims, and I do not wish to be otherwise limited to the details herein disclosed but what I claim is:—

1. In a meat chopper, a knife comprising a body member having laterally-extending recessed integral arms substantially L-shaped in cross-section and cutting blades substantially triangular in cross-section fitting the re-

cessed faces of said arms, said blades being permanently secured to said arms by a thin layer of interposed binding metal.

2. In a meat chopper, a knife comprising a body member having laterally extending recessed integral arms substantially L-shaped in cross-section and cutting blades substantially triangular in cross-section fitting the

recessed faces of said arms, said blades being permanently secured to said arms by a thin 10 layer of interposed binding metal, and said blades each having an overhanging lip engag-
ing an edge of its associated arm.

In testimony whereof I have hereunto affixed my signature.

CARL A. JOHNSON.
